G. W. WISEMAN.

POTATO HARVESTER.

APPLICATION FILED FEB. 19, 1920.

1,360,850.

Patented Nov. 30, 1920.

UNITED STATES PATENT OFFICE.

GOODWIN W. WISEMAN, OF WATERVILLE, MAINE, ASSIGNOR TO DOMINICK M. SUSI
AND NATHANIEL H. BARROWS, BOTH OF WATERVILLE, MAINE.

POTATO-HARVESTER.

1,360,850.

Specification of Letters Patent. Patented Nov. 30, 1920.

Application filed February 19, 1920. Serial No. 360,003.

To all whom it may concern:

Be it known that I, GOODWIN W. WISEMAN, a citizen of the United States, residing at Waterville, in the county of Kennebec and State of Maine, have invented certain new and useful Improvements in Potato-Harvesters, of which the following is a specification.

This invention relates to potato handling machinery and has for its object to provide a device to operate in the rear of and in conjunction with an ordinary potato digger adapted to release the potatoes from adhering dirt and providing means discharging vines and other extraneous matter.

A further object of the invention is to provide a device of the class having improved means for conveying and simultaneously agitating the potatoes traveling between the discharge of the potato digger and a storage compartment.

With these and other objects in view the device comprises certain novel units, parts and combinations as will be hereinafter claimed.

Referring to the accompanying drawing, which is made a part hereof, and on which similar reference characters indicate similar parts,

30. Figure 1 is a view of the improved potato cleaner shown in side elevation, parts being broken away to show interior construction.

Fig. 2 is a top plan view of the potato cleaner,

35. Fig. 3 is a perspective view of a section of the lag chain, the units each being broken to indicate that the chain may be of any width, and

Fig. 4 is a detail view of the trident for attaching the cleaner to the potato digger.

The improved potato cleaner which forms the subject matter of this application is adapted to be used in conjunction with a mechanical potato digger of the usual and ordinary type indicated as an entirety at A. The potato diggers in use provide means for separating from the potatoes a certain amount of dirt, and under some conditions and use in some soils the dirt will be largely discharged from the potatoes. In other soils and under other conditions, however, the amount of travel and agitation is not sufficient to dislodge from the potatoes adhering soil, nor is provision made for manually

discharging extraneous matter such as vines, stones or the like.

The present invention comprises in an organized structure side bars 10 mounted upon an axle 11, one end of which extends beyond the side rail 10 a considerably greater distance than the other as shown more particularly at Fig. 2, permitting the introduction of a running board 12 between the wheel 13 and the side rail. A wheel 14 is used upon the other end of the axle 11.

The side rails 10, forming the body of the cleaner, are normally set at an inclination and are held in such position by having their lower ends supported beneath the upper or discharge end of the digger A. Such connecting and supporting may be in any approved manner, but preferably by means of a bar 15 extending across the top and between side rails 10, with a similar bar 16 extending below the side bars of the digger. The two bars 15 and 16 are pivoted together by means of a pivot pin 17. For the purpose of bracing the connection the trident shown at Fig. 4 is employed, comprising a bar 18 extending across the digger and spaced from the bar 16 with a brace 19 extending from the middle of the bar 18 and provided with an opening 20 embracing the pivot pin 17. Side braces 21 are employed, completing the trident.

At their upper ends the side rails 10 are provided with slots 22 with journal blocks 23 slidable therein, controlled by tension screws 24, which in turn are controlled by hand wheels 25. The journal blocks 23 journal a shaft 26 upon which is carried sprocket 27. Over the sprocket 27 a chain is employed, passing also over the sprocket 29, rigidly secured to and receiving power from the traction wheel 14. The screws 24, in conjunction with the journal blocks 23, form a tightener for the chain 28, which in its course engages the sprocket 30 mounted upon the shaft 31. The shaft 31 is provided with sprockets 32 over which passes the lag chain, forming the conveyer for the potatoes. This lag chain is made up of a plurality of units having links 33 at their opposite ends, proportioned and positioned to interengage with similar links upon the next unit in series. Between the links, cross bars 34 extend, the bars being staggered, alternate bars being up and down, the bars trav-

eling on the lower level being indicated at 35 in Fig. 3, while the bars traveling on the upper level are indicated at 34.

The lag chain at its lower or forward end passes also over sprockets 36, mounted on an idle shaft. Intermediate the sprockets 32 and 36 the lag chain passes over a plurality of elliptical sprockets, one of which is shown in elevation at 37 in Fig. 1, and indicated by difference in plan area at Fig. 2. The passing of the lag chain over these elliptical sprockets tends to agitate the material carried by the lag chain, it being obvious that the chain will be raised and lowered to correspond to the difference in elevation of the different arcs of peripheries of the sprockets 37.

At the upper end a baffle 38 is provided, against which the potatoes discharged over the lag chain will engage; a hopper section 39 also is provided having an opening or chute 40 positioned to discharge into a receptacle 41 carried upon a revolving platform 42.

The long end of the axle 11 provides means to accomplish an adjustment of the wheels 13 relative to the body for operating in conjunction with rows of potatoes differently spaced. This provision may be of any type desired. It is here shown as consisting of perforations 43 with a pin 44 engaging such perforations to hold the wheel in its adjusted position upon the axle 11.

In operation the device is trailed in the rear of the digger A, propelled by any usual and ordinary draft. The movement of the cleaner imparts motion to the parts through the wheel 14, the potatoes being dumped upon the lag chain and thereby conveyed upwardly between the side bars 10 to be dumped eventually into the hopper and discharged through the chute 40 into the receptacle 41. In the course of travel along the lag chain the potatoes are subjected to agitation of the elliptical sprockets for the purpose of discharging dirt therefrom which is dropped through the open meshes of the lag chain. Stones, sticks, vines and other extraneous matter are, however, not so dumped through the chain but are manually removed by a man standing upon the running board 12 and reaching over the body of the cleaner manually removing any extraneous matter and throwing it to one side as the machine progresses. This provides for the discharge into the receptacle 21 of only the cleaned and separated potatoes.

Having thus fully described my said in-

vention, what I claim as new and desire to secure by Letters Patent is:

1. In a potato cleaner, a body, an endless apron comprising bars extending across the body and linked together, such bars being staggered, alternate bars traveling in a higher plane than the intermediate bars and agitating means supporting the apron intermediate its extremes. 60

2. In a potato cleaner, a body, wheels supporting the body, bearing sprockets journaled upon the body, a lag chain comprising an endless apron passing over the supporting sprockets, means to drive the apron from the supporting wheels, said lag chain comprising links connected by cross bars, some of which are bent upwardly from the plane of the links, and others bent downwardly from the plane of the links beneath and adjacent the upwardly bent crossbars. 70

3. In a potato cleaner, a body, wheels supporting the body, an endless apron traveling along the body and driven from the wheels, elliptical toothed agitating rollers spaced along the apron, succeeding rollers having their major and minor axes disposed at different angles driven from the wheels and adapted to impart a wave-like agitation throughout the apron whereby the potatoes are reciprocated up and down and rocked back and forth in their travel along the apron. 80

4. In a potato cleaner a traveling apron composed of interengaging links and forming cross-bars provided with offset portions formed so that alternate bars extend forward and backward, the forwardly extending portion of one bar overlying the backwardly extending portion of the adjacent bar, the successive pairs being spaced, means interposed beneath the apron for imparting varied agitation to the apron at progressive points. 90

5. In a potato cleaner, a body, an endless apron comprising bars extending across the body and linked together, such bars being staggered, alternate bars traveling in a higher plane than the intermediate bars. 95

In witness whereof, I have hereunto set my hand and seal at Washington, D. C., this 18th day of February, A. D. nineteen hundred and twenty. 100

GOODWIN W. WISEMAN. [L. S.]
